FLIGHT NAVIGATION PARTICULARS

VFR AND IFR CRUISING ALTITUDES

VFR or On Top Even Thousands MSL Plus 500 (4,500'; 6,500'; etc.)
IFR Even Thousands MSL (4,000'; 6,000'; etc.)
VFR Cruising Altitude Rule Applies Above 3,000' AGL
and Below 18,000' MSL Unless Authorized by ATC

VFR or On Top Odd Thousands MSL Plus 500 (3,500'; 5,500'; etc.)
IFR Odd Thousands MSL (3,000'; 5,000'; etc.)
ATC May Assign Different IFR Altitudes
IFR Outside Controlled Airspace All Courses Are Magnetic
